UNITED STATES PATENT OFFICE.

ALBERT C. TERRELL, OF GRAND RAPIDS, MICHIGAN.

DRAWER.

1,402,385.

Specification of Letters Patent. Patented Jan. 3, 1922.

Application filed July 30, 1921. Serial No. 488,521.

To all whom it may concern:

Be it known that I, ALBERT C. TERRELL, a citizen of the United States, residing at Grand Rapids, in the county of Kent and State of Michigan, have invented new and useful Improvements in Drawers, of which the following is a specification.

The present invention relates to drawers for cabinets, filing cases, and the like; and its object is to provide a drawer of improved construction and having parts which may be readily assembled.

This and any other objects hereinafter appearing are attained by, and the invention finds preferable embodiment in, the structure hereinafter particularly described in the body of this specification and illustrated by the accompanying drawings, in which:—

Figure 1 is a top plan view of the fore part of a drawer, a portion of the face member of the drawer's front being shown in section on a horizontal plane corresponding to line 1—1 of Figures 2 and 3;

Figure 2 is a front view of the drawer, a portion of said face member being broken away;

Figure 3 is a view in perspective of the drawer and the face member of its front in position about to be assembled; and

Figure 4 is a like view, enlarged, of the front corner of said drawer.

In the embodiment of the invention chosen for illustration by the drawings and for detailed description in the body of this specification, a drawer made of sheet metal is shown, having a bottom 1, back 2, sides 3 and front which comprises a body member 4 and a face member 5. These parts, excepting the face member 5, are securely joined together, the forward ends of the drawer sides 3 being seated and securely fastened, as by "spot welding," between the parallelly disposed side-holding portions 6 of the body member 4 of the drawer's front, said member being bent to form such portions and the outwardly extending end flanges 7, as particularly seen in Figures 1 and 4. The drawer sides are bent adjacent their upper edges to form flanges having, first outwardly extending portions 8 and then downwardly extending portions 9 which slidably bear on the casing of the drawer in the drawer's opening and closing movements.

The face member 5 of the drawer's front is bent adjacent each end to form a flange having a rearwardly extending part 10 and

then an inwardly extending part 11 vertically slidable on the body member's flange 7 and serving to hold the two members 4 and 5 of the drawer's front against relative horizontal movement.

Orifices 12 in the body member 4 and orifices 13 in the face member 5 register with each other when the face member is slid to its assembled position seen in Figures 1 and 2, whereupon the mounting parts 14 of the drawer's "pull" 15 may be thrust through these orifices to attach the drawer pull to the drawer and to lock the members 4, 5 of the drawer front together. It will be seen that by providing this two-member drawer front, the face member 5 may be painted, decorated or "finished" separately and in different style from the rest of the drawer, and also that a new face member having desired lettering and the like may be readily assembled with an old drawer.

The invention being intended to be pointed out in the claims, is not to be limited to or by details of construction of the particular embodiment thereof illustrated by the drawings or hereinbefore described.

I claim:

1. In a drawer; a sheet metal body member of the drawer's front bent adjacent each end to form parallelly disposed side-holding portions and an outwardly extending end flange; drawer sides whose forward ends are securely held between said side-holding portions; a sheet metal face member of the drawer's front having at each end an inwardly extending retaining flange vertically slidable on said body member's said flange.

2. In a drawer; a sheet metal body member of the drawer's front bent adjacent each end to form parallelly disposed side-holding portions and an outwardly extending end flange; drawer sides whose forward ends are securely held between said side-holding portions; a sheet metal face member of the drawer's front having at each end an inwardly extending retaining flange slidable on said body member's said flange in a direction parallel with the face member's front and rear sides; the body member and the face member of the drawer's front having orifices therethrough registering with each other in the assembled position of said members and adapted to receive the mounting of the drawer's pull.

3. In a drawer; a sheet metal body member of the drawer's front bent adjacent each

end to form parallelly disposed side-holding portions and an outwardly extending end flange; sheet metal drawer sides whose forward ends are securely held between said 5 side-holding portions, and bent adjacent their upper edges to form outwardly and then downwardly extending flanges; a sheet metal face member of the drawer's front

bent adjacent each end to form a rearwardly and then inwardly extending retaining flange vertically slidable on said body member's said flange.

In testimony whereof I have hereunto set my hand at Grand Rapids, Michigan, this 26th day of July, 1921.

ALBERT C. TERRELL.
